Claims priority, application Great Britain, Sept. 11, 1962, 34,737/62

4 Claims. (Cl. 317—123)

The invention relates to electrical protective relays, that is to say, to relays operative under predetermined conditions to perform a protective function for, for example, bringing about automatic de-energisation and/or disconnection of electrical plant from its source of supply.

According to the invention, an electrical time-overcurrent protective relay includes a relay operating element for energisation by an operating current supplied thereto for performing in response to such operating current a protective function after a time delay dependent upon the magnitude of the operating current, and a relay input circuit arrangement having first and second input terminals for connection with a source of unidirectional current which is to be monitored by the relay, first and second output terminals connected with the relay operating element for transmitting thereto the said operating current, shunt electric circuit means connected between the first and second input terminals and including in series with one another a non-linear resistor and an adjustable linear resistor (hereafter referred to as the first adjustable linear resistor), serial electric circuit means including first electric circuit means connected between the first input terminal and the first output terminal, and second electric circuit means connected between the second input terminal and the second output terminal, one of the said first and second electric circuit means including an adjustable linear resistor (hereafter referred to as the second adjustable linear resistor), the said non-linear resistor exhibiting alternatively a high resistance value or a low resistance value according to whether a unidirectional current carried thereby lies in a predetermined range of low values or in a predetermined range of higher values respectively, and these resistance values being such that for a predetermined range of low input current values the non-linear resistor exhibits its high resistance value and prevents adjustment of the first adjustable linear resistor having any substantial influence on the ratio 'operating current/input current', adjustment of this ratio to calibrate the relay time delay at a predetermined first input current value, lying in the said range of input current values, being obtainable by way of adjustment of the second adjustable linear resistor only, and such that for a predetermined range of higher input current values the non-linear resistor exhibits its low resistance value and enables adjustment of the first adjustable linear resistor to be effective to provide adjustment of the said ratio whereby to calibrate the relay time delay at a predetermined second input current value, lying within the said predetermined range of higher input current values, without substantially upsetting the calibration of the relay time delay at the said predetermined first input current value as determined by the setting of the second adjustable linear resistor.

Such an electrical time-over current relay may also include at least one other relay input circuit arrangement similar to the aforesaid relay input circuit arrangement, each such other relay input circuit arrangement having

2

its first and second output terminals connected to the first and second input terminals respectively of the succeeding relay input circuit arrangement, and the resistance values of the non-linear resistor of each such other relay input circuit arrangement being such that calibration of the relay time delay at a predetermined 'lower' input current value which is greater than the predetermined 'greater' input current value in respect of the succeeding relay input circuit arrangement is obtainable by adjustment of the second adjustable linear resistor of the relay input circuit arrangement without upsetting the calibration of the relay time delay as determined by the settings of the first and second adjustable linear resistors of any succeeding relay input circuit arrangement, the non-linear resistor of the relay input circuit arrangement then exhibiting its high resistance value, and such that calibration of the relay time delay at a predetermined 'greater' input current value is obtainable by adjustment of the first adjustable linear resistor of the relay input circuit arrangement without substantially upsetting the calibration of the relay time delay as determined by the setting of the second adjustable linear resistor of the relay input circuit arrangement, the non-linear resistor of the relay input circuit arrangement then exhibiting its low resistance value.

Preferably, the or each non-linear resistor means comprises one or more diodes.

An electrical time-overcurrent protective relay embodying the invention will now be described by way of example and with reference to the accompanying drawing in which:

FIG. 1 is a diagram of the circuit of the relay; and

FIG. 2 is a characteristic curve of a typical non-linear resistance device for use in the circuit of FIG. 1.

Referring to FIG. 1, the winding 10 of the relay rotor (not shown) is connected, through control spring ligaments 11 and through a two stage input circuit 12, to relay input terminals 13 connected to the circuit to be protected by the relay. The connection is made via current transforming and rectifying means (not shown) so that the relay is supplied with a direct current representing the magnitude of the alternating current in the protected circuit. The rotor is arranged to co-operate with the poles of a stationary magnet (not shown) so that a torque acting to rotate the rotor is produced when the rotor winding carries a current.

The input circuit 12 consists of two stages, one stage comprising a series resistor 14 and a shunt circuit 16 and the other stage comprising a series resistor 15 and a shunt circuit 17.

The shunt circuit 16, which is connected across the terminals 13, consists of a series arrangement of a resistor 18 and two diodes 19, 20. The shunt path 17, one end of which is connected to the junction of the resistors 14 and 15, consists of a resistor 21 in series with a diode 22.

The resistors 14, 15, 18 and 21 are all linear resistors and are all adjustable.

The input circuit 12 has the effect of causing an increasing proportion of the input current from the terminals 13 to bypass the rotor winding 10 as this input current increases. This has the effect of modifying the normal 'very inverse' time-overcurrent characteristic of the relay (by which is meant a characteristic such that the operating time of the relay is inversely proportional to the operating current) to produce a less 'inverse' characteristic.

The proportion of input current to the relay from the terminals 13 which is by-passed through the shunt paths 16, 17 depends on the relative resistances of the winding 10, the variable resistors 14, 15, 18, and 21 and the 'slope resistance' of the diodes 19, 20, 22. The slope resistance of the diodes depends on the current flowing through them, that is, on the magnitude of the input current, because of their non-linear resistance-current characteristic. The parameters of the circuit are so chosen that, with a relay input current of twice the pick-up current of the relay (that is, twice the current required to initiate movement of the rotor), the shunt path 17 is slightly conductive whilst the shunt path 16 is non-conductive.

Referring now to FIG. 2, at twice the pick-up current of the relay, the diode 22 operates at a point on its characteristic corresponding to the voltage *b*. The voltage across the diode 22 can be varied between the points *a* and *c* on the characteristic shown in FIG. 2 by adjustment of the resistor 15, so that a corresponding change can be made in the proportion of input current bypassing the rotor winding 10. This adjustment alters the operating time of the relay for a relay input current of twice the pick-up value and thus provides a means of calibration at that value of relay input current.

If the input current rises to five times the pick-up current of the relay, the point of operation of the diode 22 is moved to the point on its characteristic corresponding to the voltage *d*, that is, the diode becomes more conductive. At this level of input current, the other shunt path 16 is however still non-conductive.

At this point of operation of the diode 22, its slope resistance is only a fraction of an ohm. Therefore, adjustment of the resistor 21 has an appreciable effect on the proportion of input current which is by-passed through the shunt path 17 and hence provides adjustment of the operating time of the relay for a relay input current of five times the pick-up value, and hence a means of calibration at that value of relay input current. However, any adjustment of the resistor 21 for the purpose of calibrating the relay at five times the pick-up current has very little disturbing effect on the calibration of the relay operating time at twice the pick-up current obtained by adjustment of resistor 15 as described above, because the slope resistance of the diode 22 is much higher at twice the pick-up current than at five times the pick-up current. In other words, the proportion of input current flowing through the resistor 21 is very much lower at twice the pick-up current than it is at five times the pick-up current, and therefore any adjustment of resistor 21 will have little effect on the proportion of input current flowing through the rotor winding 10 at twice the pick-up current.

The calibration of the relay operating time at ten times the pick-up current is obtained by suitable adjustment of the resistor 14, the diodes 19 and 20 then being of high resistance, and the calibration at twenty times the pick-up current is obtained by adjustment of the resistor 18, the diodes 19 and 20 then being of low resistance. The variation in slope resistance of the diodes 19 and 20 ensures that these adjustments will not substantially affect the other calibrations obtained by adjustment of the resistors 15 and 21. Thus any deviation of the time-overcurrent characteristic of the relay from the desired shape, which deviation may for example be due to departure of the diode and/or rotor winding resistances from their nominal values, may be corrected.

It is not necessary to provide means for compensating for ambient temperature variation because the diodes 19, 20 and 22 are so chosen that their temperature coefficients of resistance are matched to that of the rotor winding so as to render the relay self-compensating for changes in ambient temperature.

What I claim as my invention and desire to secure by Letters Patent is:

1. An electrical time-overcurrent protective relay including a relay operating element for energisation by an operating current supplied thereto for performing in response to such operating current a protective function after a time delay dependent upon the magnitude of the operating current, and a relay input circuit arrangement having first and second input terminals for connection with a source of unidirectional current which is to be monitored by the relay, first and second output terminals connected with the relay operating element for transmitting thereto the said operating current, shunt electric circuit means connected between the first and second input terminals and including in series with one another a non-linear resistor and an adjustable linear resistor (hereafter referred to as the first adjustable linear resistor), serial electric circuit means including first electric circuit means connected between the first input terminal and the first output terminal, and second electric circuit means connected between the second input terminal and the second output terminal, one of the said first and second electric circuit means including an adjustable linear resistor (hereafter referred to as the second adjustable linear resistor), the said non-linear resistor exhibiting alternatively a high resistance value or a low resistance value according to whether a unidirectional current carried thereby lies in a predetermined range of low values or in a predetermined range of higher values respectively, and these resistance values being such that for a predetermined range of low input current values the non-linear resistor exhibits its high resistance value and prevents adjustment of the first adjustable linear resistor having any substantial influence on the ratio 'operating current/input current', adjustment of this ratio to calibrate the relay time delay at a predetermined first input current value, lying in the said range of input current values, being obtainable by way of adjustment of the second adjustable linear resistor only, and such that for a predetermined range of higher input current values the non-linear resistor exhibits its low resistance value and enables adjustment of the first adjustable linear resistor to be effective to provide adjustment of the said ratio whereby to calibrate the relay time delay at a predetermined second input current value, lying within the said predetermined range of higher input current values, without substantially upsetting the calibration of the relay time delay at the said predetermined first input current value as determined by the setting of the second adjustable linear resistor.

2. An electrical time-overcurrent protective relay according to claim 1, including at least one other relay input circuit arrangement similar to the aforesaid relay input circuit arrangement, each such other relay input circuit arrangement having its first and second output terminals connected to the first and second input terminals respectively of the succeeding relay input circuit arrangement, and the resistance values of the non-linear resistor of each such other relay input circuit arrangement being such that calibration of the relay time delay at a predetermined 'lower' input current value which is greater than the predetermined 'greater' input current value in respect of the succeeding relay input circuit arrangement is obtainable by adjustment of the second adjustable linear resistor of the relay input circuit arrangement without upsetting the calibration of the relay time delay as determined by the settings of the first and second adjustable linear resistors of any succeeding relay input circuit arrangement, the non-linear resistor of the relay input circuit arrangement then exhibiting its high resistance value, and such that calibration of the relay time delay at a predetermined 'greater' input current value is obtainable by adjustment of the first adjustable linear resistor of the relay input circuit arrangement without substantially upsetting the calibration of the relay time delay as determined by the setting of the second adjustable linear resistor of the relay input circuit arrangement, the non-

linear resistor of the relay input circuit arrangement then exhibiting its low resistance value.

3. An electrical time-overcurrent protective relay according to claim 1, wherein the non-linear resistor comprises a diode device.

4. An electrical time-overcurrent protective relay according to claim 2, wherein each non-linear resistor comprises a diode device.
